UNITED STATES PATENT OFFICE

143,140

DESIGN FOR A FROZEN FOOD CABINET

William S. Connell, Norwood Park Township,
Cook County, Ill., assignor to The Bastian-
Blessing Company, Chicago, Ill., a corporation of Illinois

Application June 3, 1944, Serial No. 113,845

Term of patent 7 years

(Cl. D67—3)

To all whom it may concern:

Be it known that I, William S. Connell, a citizen of the United States, residing at Norwood Park Township, in the county of Cook and State of Illinois, have invented a new, original, and ornamental Design for a Frozen Food Cabinet, of which the following is a specification, reference being had to the accompanying drawing, forming a part thereof.

Fig. 1 is a front elevational view of the frozen food cabinet, showing my new design.

Fig. 2 is a side elevational view, and
Fig. 3 is a top plan view thereof.

I claim:

The ornamental design for a frozen food cabinet, as shown.

WILLIAM S. CONNELL.
